UNITED STATES PATENT OFFICE.

HENRY V. RILEY AND CHARLES SELDEN, OF BALTIMORE, MARYLAND.

ELECTRICAL RAILWAY-SIGNAL.

SPECIFICATION forming part of Letters Patent No. 515,366, dated February 27, 1894.

Application filed October 5, 1893. Serial No. 487,305. (No model.)

To all whom it may concern:

Be it known that we, HENRY V. RILEY and CHARLES SELDEN, citizens of the United States, residing at Baltimore, in the State of Maryland, have invented certain new and useful Improvements in Electrical Railway-Signals, of which the following is a specification.

Our invention relates to the class of inventions employed for the purpose of causing an alarm to sound or a signal to be given in the neighborhood of a grade crossing when trains are approaching in either direction on a railroad track.

The invention consists of two electro magnets oppositely arranged, said magnets are continuously wound in two circuits common to a single battery, and a polarized armature arranged between said magnets, also suitable contact points and a signal circuit so that trains in one direction upon the track will cause the signal to operate at a given point, while trains in the opposite direction at the same point will not cause the signal to operate.

In the drawing, the circuits are shown working to the earth, though we desire it understood that a return wire may be used if desired.

a a' are two electro magnets continuously wound and oppositely arranged and containing between the pole pieces thereof a polarized armature *b*. This pair of magnets are wound differentially, but not in like proportions, the wire *X* having a less number of convolutions and therefore a less magnetic effect upon the magnets than the wire *P*, which is so wound as to have a largely increased magnetic effect when charged with current.

Reference letters *K M* and *L M* represent suitable circuit closers of any approved pattern, located at one end of a section of road to be protected; and *K' M'* and *L' M'* are similar devices located at the opposite end of said section.

S represents the signal circuit, *H'* the battery for operating the same and *B* a suitable signal, in this instance a bell, although it may be a visual signal.

G G' are contact points controlled by the vibrations of armature *b*.

H represents the main line battery.

The operation is as follows:—A train approaching in the direction indicated by the

arrow would, upon reaching point *L M*, charge the magnets through wire *P* and cause the armature *B* to be attracted by magnet *a'* and repelled by magnet *a* with equal force, thereby holding the contact points *G G'* apart, at another interval of time when points *K* and *M* may be reached, wire *X* is also charged, but on account of its winding, the attraction of magnet *a* and repulsion of magnet *a'* are less than that of wire *P* and hence the contact points *G G'* remain apart, it being understood that the charge in wire *P* tends to create a certain polarity in magnets *a* and *a'*, while the charge in wire *X* tends to create exactly the opposite polarity to that created by wire *P*, but as the effect from wire *P* is greater than from wire *X*, there is a balance of power or bias in favor of wire *P*, hence when both wires are charged simultaneously, the action of the magnets tends to keep points *G G'* separated, until the last pair of wheels of the train having left point *L* and broken contact there closes the points *K* and *M* so that the circuit is at this time through one wire only and in such direction as to cause the armature to be attracted by magnet *a* and repelled by magnet *a'* with equal force but, as will be understood, of less power than when energized by wire *P* thereby bringing together contacts *G G'* and closing circuit *S* and operating signal *B*. Now by reason of the fact that armature *b* is polarized it will remain in this last position assumed and thereby hold the signal circuit closed and the signal operated until the train reaches point *L' M'* when the circuit being closed through wire *P* the armature is attracted by magnet *a'* and repelled by magnet *a* thereby separating contacts *G G'* opening circuit *S* and discontinuing the operation of the signal. The armature as stated being polarized remains in contact with the pole piece of magnet *a'* until magnet *a* is energized. A train proceeding in the opposite direction would be exactly the reverse operation. Hence it would be seen that even on a single track, by reason of the bias magnet winding, we can so arrange that trains in one direction will cause an alarm to be operated from a given point, yet should a train pass that same given point in the opposite direction the alarm would not be operated.

We desire it to be understood that while

we have shown the track circuit closers as an ordinary means of closing the circuit, we do not wish to confine ourselves to this form; we reserve the right to make any change of form 5 that may fall within the scope of our invention.

Having described our invention, what we claim, and desire to secure by Letters Patent, is—

- 10 1. A differentially wound polarized relay, the winding in one direction being greater than that in the other, so that when the circuit is closed through both windings during the same interval of time, the operation of the magnet shall be such as will cause its local points to assume a certain position as and for the purpose set forth.
- 15 2. In an electric railway signal, two differentially wound electro magnets, arranged oppositely upon a single base, a circuit closing polarized armature adapted to vibrate between said magnets, the convolutions of one differential winding being of greater number than that of the other winding, and these windings being such that a bias in favor of one is maintained over the other, substantially as described.
- 20 3. In an electric railroad signal, a device for operating the same, consisting of two differentially wound electro magnets, arranged oppositely upon a suitable base, one of the windings having a greater number of convolutions than the other, a polarized armature arranged therebetween and adapted to be simultaneously attracted by one and repelled by the other of said electro magnets, suitable circuit closing mechanism arranged upon said armature, whereby upon the attraction of said armature toward one electro magnet, 25 the electric circuit controlling the signal is closed, and upon the movement of the armature toward the other electro magnet the signal circuit is broken, substantially as described.
- 30 4. In a railway signaling system, two independently operated circuit closing devices arranged in close proximity and at each end of a section of road to be protected, two oppositely arranged differentially wound electro magnets both located in two substantially independent circuits and electrically connected together, and each controlled respectively by two circuit closing devices, a polarized armature adapted to be simultaneously attracted and repelled by the energization of said magnets, and open and close alternately a signaling circuit, whereby upon the passage of a train over the protected section a signal is given and discontinued upon the train passing out of the said section, substantially as described.
- 40 5. In a railway signaling system, two independently operated circuit closing devices ar-

ranged in close proximity at each end of a section of road to be protected, two oppositely arranged differentially wound electro magnets, both located in substantially independent circuits and electrically connected together, and each controlled respectively by two circuit closing devices, a polarized armature adapted to be simultaneously attracted and repelled by the energization of said magnets and open and close alternately a signaling circuit, whereby upon the passage of a train over the protected section a signal is operated, and discontinued upon going out of said section.

6. In a railway signaling system, two electric circuits each containing therein two electro magnets differentially wound, the winding of said magnets having a greater number of convolutions in one direction and less in the other, a polarized armature held between the pole pieces thereof, whereby upon the simultaneous energization of said magnets, the armature is attracted by one and repelled by the other, in either direction, with equal force, substantially as described.

7. In a railway signaling system, three independent electric circuits, one containing therein a signaling device, and the other two oppositely arranged electro magnets, differentially wound, the convolutions thereof being greater in one direction and less in the other, a polarized armature arranged therebetween and adapted to close when in one position, and open when in another, the signaling circuit; two independent circuit closing devices arranged in close proximity and at each end of a section of railroad to be protected, 90 said devices operating to close respectively the circuits, including the oppositely wound convolutions, whereby upon the passage of a train into the protected section, the circuit closing devices are operated, the first causing the armature to be equally attracted by one and repelled by the other of the electro magnets, thereby opening the signaling circuit, and the second causing said armature to be likewise attracted and repelled in the opposite direction and thereby closing the signaling circuit, but said armature being biased in favor of the first position assumed, and by reason of the continued operation of the first circuit closer, by reason of the passing train, 95 remaining so until the last pair of wheels of said train passes off, substantially as described.

In testimony whereof we affix our signatures in the presence of two witnesses.

HENRY V. RILEY.
CHARLES SELDEN.
